US0D1078846S

(12) **United States Design Patent** (10) **Patent No.:** **US D1,078,846 S**
Zou (45) **Date of Patent:** **** Jun. 10, 2025**

(54) **NON-SLIP STICKER**

(71) Applicant: **Shenzhen Qianhai Weizhisheng Internet Technology Co., Ltd.**, Shenzhen (CN)

(72) Inventor: **Li Zou**, Shenzhen (CN)

(73) Assignee: **Shenzhen Qianhai Weizhisheng Internet Technology Co., Ltd.**, Shenzhen (CN)

(**) Term: **15 Years**

(21) Appl. No.: **29/874,794**

(22) Filed: **Apr. 25, 2023**

(30) **Foreign Application Priority Data**

Feb. 21, 2023 (CN) 202330064625.4

(51) **LOC (15) Cl.** **06-11**

(52) **U.S. Cl.**

USPC **D6/587; D6/582**

(58) **Field of Classification Search**

USPC D19/1, 2, 3, 4, 5, 6, 7, 8, 9, 10, 11, 12; D20/10, 11, 12, 13, 18, 19, 22, 23, 24, D20/25, 26, 27, 28, 29, 30, 31, 32, 40, D20/42, 99; D6/582, 587, 592

CPC G09F 3/00; G09F 3/04; G09F 3/08; G09F 3/10; G09F 5/04; G09F 7/00; G09F 7/12; G09F 2007/127; G09F 5/00; G09F 9/00; A23V 2002/00
